ELECTRON DISCHARGE DEVICE

Robert Adler, Chicago, Ill., assignor to Zenith
Radio Corporation, a corporation of Illinois

Application March 18, 1948, Serial No. 15,713

16 Claims. (Cl. 313—82)

1

This invention relates to electron discharge devices, and more particularly, to such devices as those disclosed and claimed in my co-pending application, Serial No. 7864, filed February 12, 1948, for Electron Discharge Devices, now United States Patent No. 2,511,143, issued June 13, 1950, and which is assigned to the same assignee as the present application.

In the aforementioned co-pending application, there is disclosed and claimed a novel type of electron tube which provides improved inherent limiting characteristics by way of improving the transconductance of a control grid. Improved transconductance of the control grid is effected by locating the control grid in a position along the electron stream following an accelerating electrode having an aperture, the width of such aperture being less than the distance between such aperture and the control grid.

Also shown in the aforementioned co-pending application, as a preferred embodiment, is a novel electron tube which, together with its associated circuit elements, functions simultaneously as an amplitude limiter and a frequency demodulator. This preferred embodiment comprises, in essence, two control systems cascaded along a single electron stream, each of such systems including a high transconductance control grid, and is particularly well adapted for use as a combination amplitude limiter and frequency demodulator in a frequency modulation radio receiver.

In such an application, it is particularly desirable that substantially all amplitude modulation appearing in the input circuit be rejected. While the device set forth as the preferred embodiment in the aforementioned co-pending application rejects substantially all amplitude modulation of the input signal at low signal input levels, it has been found in practice that impaired amplitude modulation rejection is encountered in the case of large signal input levels, i. e., signal inputs greater than about 20 volts. Such impaired amplitude modulation rejection may be traced to changes, in response to changes in the input signal level, in the degree of convergence or divergence of the electron beam as it impinges upon the second or quadrature grid.

It is a primary object of the present invention to provide an electron discharge device of the type described which is particularly suited for use as a combination amplitude limiter and frequency demodulator, the amplitude modulation rejection being substantially independent of the input signal level.

In accordance with the invention, a new and

2

improved electron-discharge device comprises, in the order named, an electron gun for projecting an electron beam, an accelerating electrode having an aperture registering with the beam, a control grid, and an additional electrode responsive to an applied unidirectional operating potential for producing an accelerating electrostatic field adjacent the control grid on the side thereof remote from the electron gun. The control grid is provided with a bulged central portion extending toward the aperture of the preceding accelerating electrode and spaced therefrom by a distance greater than at least one of the transverse dimensions of that aperture.

15 The term "aperture," as employed throughout the specification and in the appended claims, is intended to define the entire electron-permeable portion or area of an otherwise electron-impermeable electrode.

20 The features of the present invention which are believed to be novel are set forth with particularity in the appended claims. The invention, together with further objects and advantages thereof, may more readily be understood, however, by reference to the following description taken in connection with the accompanying drawings, in which like reference numerals indicate like elements, and in which:

25

Figure 1 is a schematic representation of the electrode arrangement in a preferred embodiment of an electron discharge device constructed in accordance with the invention.

30 Figure 2 is a graphical representation of operating characteristics of an electron discharge device constructed in accordance with the schematic representation of Figure 1.

35 Figure 3 is a graphical representation of certain voltage and current relationships in a device such as that shown schematically in Figure 1.

40 Figure 4 is a schematic representation of another embodiment of the invention.

45 Figure 5 is a schematic circuit diagram, incorporating the device schematically shown in Figure 1, of a combined limiter-discriminator stage of a frequency modulation radio receiver.

50 Figure 6 is an idealized graphical representation of the demodulator characteristic of the circuit shown schematically in Figure 5.

Figure 7 is an exploded perspective view, partly in section, of a present preferred physical embodiment of the invention.

Figure 8 is a transverse section taken at 8—8 of Figure 7.

Figure 9 is a schematic representation of the 55 electrode arrangement of an electron discharge

device constructed in accordance with another embodiment of the present invention.

It is to be understood throughout the specification and claims that, in all cases, the tube electrodes must be arranged within an evacuated envelope.

Referring now to Figure 1, there is shown a schematic representation of the electrode arrangement of an electron discharge device constructed in accordance with the present invention. A plurality of electrodes are arranged in substantially symmetrical relation with respect to a reference plane, indicated by the letter R, such electrodes including, in the order named, a cathode 10, a first accelerating electrode 11, a first control grid 12, a second accelerating electrode 13, a second control grid 14, and an anode 15. A beam forming or directing plate 16, constructed of electrically conductive material, is arranged to surround the cathode 10 in such a way that electrons emitted by the cathode are formed into a convergent beam. The first accelerating electrode 11 is provided with a centrally located aperture or slot 17, which registers with the electron beam; a positive potential appearing on electrode 11 results in an accelerating field between slot 17 and cathode 10. Outwardly extending portions 18 and 19 may be provided on each side of slot 17 to adjust the refractive power of the slot; it is preferred that portions 18 and 19 extend parallel to the axis and in both directions from slot 17, in order to insure that electrons emitted from the cathode are formed into a substantially parallel beam in the region between electrodes 11 and 12.

Focusing means 20, such as a pair of rods or a member having a slot, preferably are inserted between the accelerating electrode 11 and the grid 12. Focusing means 20 insure that all the electrons emerging from slot 17 are directed to the grid 12 in a substantially parallel beam.

As disclosed in my above mentioned co-pending application, it has been found that whenever the distance from aperture 17 to the control grid 12 is large compared to the width of the aperture 17 itself, it is possible to adjust the field configurations, by suitable location of the various electrodes and suitable selection of the operating potentials applied thereto, in such a manner that unusually high transconductance is obtained over a narrow range of voltages applied to control grid 12, while at more negative voltages the anode current remains zero and at more positive voltages it remains constant.

The second accelerating electrode 13 is provided with a slot or aperture 21 which registers with the electron beam projected through the first grid 12. Extending portions 22, extending on each side of slot 21 toward the first grid 12, are provided to produce the desired field configuration. The second control grid 14 is provided with a bulged or formed central portion 23 which extends toward the aperture 21 in the second accelerating electrode 13. Anode 15 is provided with a bulged or formed central portion 24 substantially similar in contour to the central portion 23 of the second control grid 14. Second focusing means 25 are inserted between the slot 21 in the second accelerating electrode 13 and the second grid 14, and means 25 also serve as an electrostatic shield for minimizing inter-grid capacitance.

In order to insure that the electron beam projected into aperture 21 of the second accelerating electrode 13 be substantially parallel upon

emergence from aperture 21, the first control grid 12, in the preferred embodiment, is made plane or unformed. In addition, the contour of first focusing means 20 is adapted in a preferred way to insure substantially perpendicular incidence of the electron beam on the first grid 12, thereby to approach maximum transconductance of the input grid.

In the device of Figure 1, the input grid 12 has associated therewith an anode operating characteristic resembling a step function, with a region of constant anode current separated from the zero anode current region by a narrow region of high transconductance. By suitably spacing and arranging the electrodes, the constant anode current region may be made to commence at a negative value of input grid voltage.

Since the electron stream passes through the first grid in the form of a concentrated beam, 20 it may be directed through a second system comprising the second slot 21 and the second grid 14, similar to the first system comprising the first slot 17 and the first grid 12. The second grid 14 has a characteristic substantially similar to that of the first grid 12 but of lower transconductance, provided that the first grid is operated within the constant current region.

The device shown in Figure 1 is particularly suited for use in a frequency modulation radio receiver, combining in a single electron stream the functions of amplitude limiter and frequency demodulator.

In my above mentioned co-pending application, there is disclosed and claimed a device similar to that shown in Figure 1, the only difference being that no bulged or formed central portions 23 and 24 are provided on the second grid 14 and the anode 15. In that application, there is shown an idealized representation of the anode current-input grid voltage characteristic of a tube of this nature. This idealized representation is reproduced in Figure 2 of this application as the curves 30, 31, and 32. Curve 30 is the characteristic when the voltage E_{c2} on the second or quadrature grid 14 exceeds the level E_2 required for limiting, while curve 31 represents the characteristic when E_{c2} equals zero and curve 32 represents the idealized characteristic for some arbitrary negative value of E_{c2} . It has been found, however, that in practice, the operating characteristics deviate somewhat from the idealized characteristics 31 and 32, such practically realizable characteristics being shown as curves 31A and 32A respectively. The result of these practical deviations is impaired amplitude modulation rejection, such impaired rejection being particularly noticeable at large signal input levels E_1 . The provision of central bulged portions 23 and 24 on the quadrature grid 14 and the anode 15 (Figure 1), in accordance with the present invention, results in operating characteristics as shown in Figure 2 as curves 31B and 32B, such characteristics very closely approaching the idealized characteristics 31 and 32.

The operation of the device shown in Figure 1 is as follows. The tube comprises a pair of control grids 12 and 14 arranged in cascade. These grids may be compared with a pair of interrupter switches, the passage of current to the anode 15 being dependent on both switches being closed. An input signal applied to the first grid 12 results in a substantially square wave space current within the tube, the conducting and nonconducting periods being equal in length. If a signal of the same frequency is applied to the second grid

14. space current flows only during those periods when the signals applied to both grids are simultaneously positive. If the signal applied to the second grid 14 is shifted 90 degrees with respect to the signal applied to the first grid 12, anode current flows during one quarter of the cycle, while no anode current flows during the remaining three quarters of the cycle. The average anode current I_b , therefore, is one fourth the maximum instantaneous value of space current. Variation of the phase displacement between the two signals produces corresponding variations in length of the conductive periods, and therefore, in the average anode current. Such a characteristic is exactly what is desired for a combined limiter-discriminator stage in a frequency modulation radio receiver.

The switching action may be more fully understood by referring to Figure 3, in which certain relevant voltage and current relationships are graphically depicted. In this figure, conditions are illustrated for the case in which the voltage applied to the quadrature grid lags exactly 90 degrees behind the voltage applied to the input grid. Two conditions are illustrated, one based on a relatively large input signal voltage e_{g1} , and the other based on a much smaller input signal voltage e_{g1}' . In order to simplify the explanation, sinusoidal waveforms, and a constant signal e_{g2} on the quadrature grid, are assumed.

That interval during which the signals applied to both grids are simultaneously positive, so enabling the space current to reach the anode, extends approximately from the instant denoted by the phase angle of 90 degrees to that denoted by 180 degrees. More accurately, anode current starts to flow at the time corresponding to the vertical line 40 when the voltage e_{g2} on the quadrature grid becomes more positive than its cutoff potential E_{g2} ; the anode current reaches its full intensity at the time corresponding to vertical line 41 when the quadrature grid, its voltage still rising, attains the limiting level potential E_2 . During the period of rising anode current between times 40 and 41, the potential of the first grid is greater than the potential E_1 required for limiting; thus, operation in the region of constant current is assured, and the anode current during this period is not affected by the potential of the input grid. If an input signal e_{g1} , which is large in comparison with E_1 , is applied to the input grid, the anode current i_b continues to flow with its full intensity until the time, marked by the vertical line 42, that the input grid, its voltage decreasing, becomes more negative than the limiting level potential E_1 . At this time, the anode current i_b begins to drop and reaches zero at the time, marked by line 43, that the input grid reaches cutoff E_{g1} . It then remains zero until, approximately three quarters of a cycle later, the entire sequence is repeated.

If, now, the signal applied to the input grid is decreased to a smaller amplitude e_{g1}' , the constant anode current no longer flows until the time corresponding to line 42, but the anode current i_b' begins to drop at the earlier time corresponding to line 44. On the other hand, the decrease in anode current occurs much more slowly and zero anode current is not reached until the time corresponding to line 45, considerably later than it was reached in the case of larger input signal amplitude.

The instantaneous variation of the anode current with respect to time is plotted in the lower part of Figure 3 for both input signal amplitudes.

It is seen that the steep slope of decreasing anode current i_b in the case of the large input signal amplitude e_{g1} is intersected symmetrically by the more gradual slope i_b' corresponding to the smaller signal amplitude e_{g1}' . The point of intersection of the two slopes corresponds exactly to the phase angle of 180 degrees.

In plotting the anode current in Figure 3, it has been assumed that the control characteristic 10 of the input grid is approximately straight and symmetrical and that the control characteristics of the quadrature grid correspond to the idealized curves 31 and 32 in Figure 2. With these assumptions, the area of the trapezoid bounded by the 15 anode current curve is not changed by the transition from the steep slope to the more gradual slope. Therefore, the average anode current I_b remains unchanged as the input signal amplitude is varied, provided only that the input signal amplitude is sufficiently greater than the limiting level potential E_1 that the entire space current reaches the anode for at least a portion of the 20 cycle.

In practice, however, as already set forth, the 25 operating characteristics of a tube such as that disclosed and claimed in my above mentioned co-pending application deviate considerably from the idealized characteristics, such practical characteristics being shown as curves 31A and 32A 30 (Figure 2). While these characteristics have no bearing on the behavior of the tube during that long period (between lines 41 and 42 in Figure 3) when it operates in the constant anode current region, they influence the short period at the 35 beginning of the conductive cycle, between lines 40 and 41, when the input grid is at its positive peak and the quadrature grid is rising from cut-off E_{g2} to the limiting level E_2 . During that period, amplitude modulation of the input signal e_{g1} may produce corresponding audio frequency components in the anode current. This effect is particularly pronounced at large input signal levels, since the characteristics diverge at a greater rate at such levels.

45 While it would seem possible to improve the amplitude modulation rejection by increasing the transconductance of the quadrature grid, thereby shortening the length of the transition period, it has been found in practice that increasing the transconductance of the quadrature grid results 50 in further deviation of the operating characteristics 31A and 32A from the ideal conditions 31 and 32. Thus, a compromise is required between a desired maximum transconductance on the one hand and parallel straight operating characteristics on the other.

The deviation of the practical operating characteristics 31A and 32A from the idealized curves 31 and 32 may be explained in terms of a change 60 in the focus of the electron beam as it leaves the slot 21 in the second accelerating electrode 13 (Figure 1). The input grid 12, focusing means 20, and the second accelerating electrode 13 together function as an electron lens, the focal length of 65 which lens varies as the potential on the input grid is made more positive; the width of the beam in the plane of the input grid also decreases with an increase in the positive potential on the input grid. The combined result of these lens effects 70 is a gradual transition from divergence to convergence of the electron beam emerging from slot 21 in the second accelerating electrode 13 as the potential of the input grid 12 is made more positive.

75 Now, the second system consisting of the sec-

ond accelerating electrode 13, the second control grid 14, anode 15, and second focusing means 25 (Figure 1) functions properly only when the injected beam of electrons is properly focused and has the proper intensity for a given accelerating electrode potential. More strictly speaking, beam current, accelerator potential, and beam trajectories must be such that full space charge saturation according to Child's law can exist between the accelerating slot and the control grid. For a given beam current, accelerator potential, and accelerator-grid spacing, this condition is satisfied by one and only one degree of convergence or divergence of the original beam. If the beam diverges more, full space charge saturation is not obtained and the transconductance drops. If the beam diverges less (or converges more), space charge saturation is produced before the beam reaches the control grid, and instability results. In practice, the angle of convergence or divergence may not be large, and, for any one condition, it would be possible to place the control grid at the proper distance from the accelerator to obtain high transconductance and stable operation. To accommodate the range of conditions produced by the variable focusing effects, however, it would be necessary to provide means for varying the accelerator-grid spacing; in other words, the distance between accelerator and grid would have to be decreased in response to an increase in the positive potential on the input grid 12.

In accordance with the present invention, the quadrature grid 14 is provided with a bulged central portion 23 extending toward the slot 21 in the second accelerating electrode 13. It is observed that whenever the beam emerging from slot 21 is divergent, the grid 14 is intersected over nearly its full width, and whenever the beam emerging from slot 21 is convergent, it strikes only a small central portion of this grid. In this manner, it is possible to maintain nearly the same degree of space charge saturation throughout a wide range of focusing conditions; of course, some sacrifice in transconductance is made.

Were the anode plane, the warped configuration of the second grid 14 would result in a non-uniform field between such grid and the following anode 15, and therefore, in variable-mu effects between the second grid and the anode. As is well known in the art, such variable-mu effects reduce the transconductance. In order to maintain a substantially uniform unidirectional accelerating electrostatic field between grid and an anode, the anode 15 is preferably provided with a bulged central portion 24 substantially similar in contour to the central portion 23 of grid 14.

With a device constructed in accordance with Figure 1, operating characteristics 31B and 32B, more nearly approaching the ideal characteristics, 31 and 32 respectively, may be obtained, and improved amplitude modulation rejection may be attained.

It has previously been explained that changes in the control characteristics of the second control grid occur whenever the potential on the first control grid is varied, and that these changes are caused by a variation of the angle of convergence or divergence of the beam projected onto the second control grid. It has also been explained how, according to this invention, such variations in control characteristics are compensated for by the bulged shape of the second con-

trol grid. In combination with an anode of similar contour, a very considerable improvement in control characteristics is realized. The same concept, however, is capable of a somewhat broader interpretation which permits an even closer approach to the ideal of straight, parallel, horizontal characteristics.

In practice, it is frequently found that a structure according to Figure 1, while providing characteristics which are greatly improved over structures not embodying the bulged grid, still yields characteristics which have a tendency to deviate from horizontal lines within some ranges of voltage applied to the first control grid 12. For example, in a practical tube, the characteristics tend to slant upward in the range of input voltages E_{ci} between zero and +10 volts, then becomes substantially horizontal, and finally tend to slant slightly downward at input voltages above about +30 volts.

It has been found that it is possible to compensate for such change in slope in response to potential variation of the input grid by introducing an intentional variation of the static amplification factor of the system formed by the second grid 14 and the anode 15. For instance, in the above mentioned example, the anode may be brought closer to the second control grid at its extreme marginal portions 100 which are most distant from the central plane R of the electron beam, as shown in Figure 4. As has been previously explained, the beam reaches these marginal portions only when the potential applied to the first control grid 12 is zero or very little positive. Under these conditions, increased anode current is drawn in the marginal portions because of the increased field intensity due to the smaller spacings. As the voltage E_{ci} on the first control grid 12 is made more positive, the width of the beam is reduced and the marginal portions no longer contribute to the characteristics of the second grid 14. The initial portion of the control characteristics of this grid is therefore lifted without a substantial effect on the remaining portion.

A similar effect may be accomplished at the highly positive potentials on the first grid by having the central portion of the anode 15 come closer to the second control grid 14.

More broadly speaking, it is possible to compensate for a residual curvature in the characteristics of the second control grid 14 with reference to the positive potential E_{ci} on the first control grid 12, by so shaping the anode 15 that the relative spacing between the anode and the second control grid 14, plotted as a function of the distance from the extreme marginal portions of the anode toward the central plane R of the electron beam, increases and decreases in substantially the same manner in which the uncompensated control characteristics, plotted from zero voltage E_{ci} toward more positive potentials, rise and fall.

There is shown in Figure 5 a schematic circuit diagram of a combined amplitude-limiter and frequency demodulator which utilizes a tube constructed in accordance with Figure 1. Input signals are applied to the first grid 12 from the output of the customary intermediate frequency amplifier (not shown) by way of input terminals 50 and 51. Suitable constant operating bias voltage is supplied by means of a cathode bias resistance 52 and associated bypass capacitance 53 arranged in circuit with the cathode 10 in the customary manner. The accelerating elec-

trodes 11 and 13 are interconnected, either internally or externally, and connected to the positive terminal of a suitable source of positive unidirectional operating potential, here shown as a battery 54, the negative terminal of which source is connected to terminal 51. An oscillatory circuit 55, comprising an inductance 56 and a capacitance 57, is connected between the second grid 14 and terminal 51. It is to be understood that capacitance 57 may comprise the distributed capacitance of the circuit, in which case no separate unitary circuit element 57 appears. Audio frequency output voltage is derived from an anode load resistance 58, connected between the anode 15 and the positive terminal of source 54, by means of a pair of output terminals 59 and 60. Output terminals 59 and 60 are bypassed for the intermediate frequency by a capacitance 61.

In operation, the parallel resonant circuit 55 is tuned to resonate at the intermediate frequency. As is taught by Zakariás in his U. S. Patent No. 2,208,091, a unilateral space charge coupling exists from the input grid 12 to the quadrature grid 14. That is to say, a voltage is induced on the second grid 14 by the space current passed from the first grid 12; however, the potential of the first grid 12 is unaffected by the potential variation of the second grid 14. This space charge coupling between grids is equivalent phasewise to a one way negative capacitance; consequently, the voltage induced on the second grid 14 lags the voltage of the first grid 12 by exactly 90 degrees whenever the input voltage varies at exactly the frequency to which the oscillatory circuit 55 is tuned. Frequency deviation of the input voltage applied to grid 12 results in a change in the phase displacement between the voltages appearing on the first and second grids 12 and 14, and thus in a change in the average anode current. As a result, the output voltage appearing across output terminals 59 and 60 varies in amplitude in accordance with the frequency variation of the input signal applied between input terminals 50 and 51.

The circuit described is substantially unresponsive to amplitude variations of the input signal because of the relations explained in connection with Figure 3. The response to amplitude variations of the input signal is further reduced by the substantially constant amplitude of the quadrature signal, which develops on the second grid 14 as a consequence of unilateral space charge coupling from the input grid 12 for all input signal voltages exceeding a certain minimum. This stability of the quadrature voltage results from the fact that the space charge which develops in the vicinity of the quadrature grid 14 is a function of the space current, and that in a tube constructed in accordance with this invention, the space current varies between zero and a constant intensity.

The demodulator characteristic for the circuit shown and described in Figure 5 is shown in Figure 6 as curve 70. The demodulator characteristic for the well-known combination of an amplitude limiter and a conventional double-diode phase sensitive discriminator is shown as the dotted curve 71, the coordinate axes of curve 71 having been displaced for the purpose of facilitating comparison between the two systems. The output of the demodulator of Figure 5 is similar to that of the double-diode discriminator within the substantially linear region, and the characteristic peaks of curve 71 are absent in the case of curve 70. It is to be noted that the

circuit shown in Figure 5 provides a wider linear region of operation than the conventional circuit, thus permitting improved tuning and greater output.

5 There is shown in Figure 7 an exploded perspective view, partly in section, of a combination limiter-discriminator tube constructed in accordance with the arrangement shown and described in connection with Figure 1. The electrodes are 10 supported between a pair of mica tube mounts 80 and 81 within an evacuated envelope 82, the customary getter 83 being provided for absorbing any residual gas after evacuation. The electrodes are brought out through a sealed base 84 to respective terminals or pins 85.

Figure 8 is a transverse section taken at 8-8 of the view of Figure 7, and is included in order to show more completely the structure of such a tube.

20 Merely by way of illustration, and in no sense by way of limitation, it has been found that the following dimensions may be used in producing a tube of the type shown and described in connection with Figures 1, 7 and 8.

	Inch
Width of cathode 10	.050
Width of slot 17	.030
Distance from cathode 10 to slot 17	.112
Length of extending portions 18	.047
Length of extending portions 19	.025
Width of input grid 12	.106
Distance from slot 17 to grid 12	.101
Width of slot 21	.050
Width of quadrature grid 14	.178
Distance from slot 21 to grid 12	.072
Distance from slot 21 to central portion 23 of grid 14	.093
Distance from slot 21 to main portion of grid 14	.123

40 All electrodes have a longitudinal dimension of $\frac{1}{8}$ of an inch. All of the sheet metal electrodes are constructed of 4-mil stock. The input grid 12 is formed by mounting 88 turns per inch of 1.5-mil wire on a pair of supporting rods, and the quadrature grid 14 is constructed in a similar manner, using 80 turns per inch of 2-mil wire. In addition, the accelerating electrodes 11 and 13 are internally interconnected, as are the cathode 10, the beam forming plate 16, the focusing electrode 20, and the shield 25, in order to minimize the number of external connections.

45 While the present invention has been shown and described in connection with a present preferred embodiment specifically suitable for use as a combined amplitude limiter and frequency demodulator in a frequency modulation radio receiver, and while the objects and advantages of the invention have been pointed out in connection with improved amplitude modulation rejection, one other very important advantage accrues from the use of the present invention. The warped configuration of the quadrature grid results in a space charge saturation between the 50 accelerating slot preceding the grid and the grid itself which is substantially independent of small changes in the degree of convergence or divergence of the electron beam impinging on the grid. In practice, and particularly in mass production, 55 it has been found that small changes in the focusing of the electron beam result from variations in the dimensions of and the spacing between the various electrodes within the tolerances practically attainable with mass production techniques. Such changes in the focus of the elec-

tron beam result in a considerable nonuniformity of operating characteristics between individual tubes constructed with unformed control grids, such as disclosed and claimed in my aforementioned co-pending application. The present invention, however, by automatically compensating for such small changes in focus, results in a substantial uniformity of operating characteristics between individual tubes while maintaining practical manufacturing tolerances.

Thus, in accordance with the present invention, and of course with some sacrifice of transconductance, substantial uniformity of operating characteristics may be obtained in electron discharge devices comprising a single control system, such as shown and described in Figure 2 of my aforementioned co-pending application.

There is shown in Figure 9 a device of this type incorporating the present invention. The structure shown schematically in Figure 9 is substantially the same as the first portion of the structure schematically shown in Figure 1, the second control system of Figure 1 comprising the second accelerating electrode 13, second focusing means 25, second control grid 14, and anode 15 being replaced by a single anode 80. The configuration of focusing means 20 is simplified to comprise a relatively large aperture, and extending portions 19 on either side of slot 17 of the first accelerating electrode 11 have been eliminated.

In accordance with the present invention, the control grid 12 is provided with a formed or bulged central portion 81 extending toward the slot 17 in the accelerating electrode 11. In order to maintain a substantially uniform accelerating field in the region between control grid 12 and anode 80, the anode is provided with a central bulged portion 82, substantially similar in contour to the central portion 81 of control grid 12.

While there have been shown and described certain present preferred embodiments of the invention, it is to be understood that numerous variations and modifications may be made, and it is contemplated, in the appended claims, to cover all such modifications as fall within the true spirit and scope of the invention.

I claim:

1. An electron discharge device comprising in the order named: an electron gun for projecting an electron beam; an accelerating electrode having an aperture registering with said beam; a control grid having a bulged central portion extending toward said aperture and spaced therefrom by a distance greater than at least one of the transverse dimensions of said aperture; and an additional electrode responsive to an applied unidirectional operating potential for producing an accelerating electrostatic field adjacent said grid on the side thereof remote from said electron gun.

2. An electron discharge device comprising in the order named: an electron gun for projecting an electron beam; an accelerating electrode included in said electron gun and having an aperture registering with said beam; a control grid including a plurality of substantially parallel conducting elements disposed across the path of said beam and having a bulged central portion extending toward said aperture and spaced therefrom by a distance greater than at least one of the transverse dimensions of said aperture; and an additional electrode responsive to an applied unidirectional operating potential for producing an accelerating electrostatic field adjacent said

grid on the side thereof remote from said electron gun.

3. An electron discharge device comprising in the order named: an electron gun for projecting an electron beam; an accelerating electrode included in said electron gun and having an aperture registering with said beam; a control grid having a bulged central portion extending toward said aperture and spaced therefrom by a distance greater than at least one of the transverse dimensions of said aperture; and an anode of contour substantially similar to that of said grid.

4. An electron discharge device comprising in the order named: an electron gun for projecting a sheet-like electron beam of substantially rectangular cross-section; an accelerating electrode having a slot registering with said beam; a control grid having a bulged central portion extending toward said slot and spaced therefrom by a distance greater than the smallest transverse dimension of said slot; and an additional electrode responsive to an applied unidirectional operating potential for producing an accelerating electrostatic field adjacent said grid on the side thereof remote from said electron gun.

5. An electron discharge device comprising in the order named: an electron gun for projecting a sheet-like electron beam of substantially rectangular cross-section; an accelerating electrode included in said electron gun and having a slot registering with said beam; a control grid including a plurality of substantially parallel conducting elements disposed across the path of said beam and having a bulged central portion extending toward said slot and spaced therefrom by a distance greater than the smallest transverse dimension of said slot; and an additional electrode responsive to an applied unidirectional operating potential for producing an accelerating electrostatic field adjacent said grid on the side thereof remote from said electron gun.

6. An electron discharge device comprising in the order named: an electron gun for projecting a sheet-like electron beam of substantially rectangular cross-section; an accelerating electrode included in said electron gun and having a slot registering with said beam; a control grid having a bulged central portion extending toward said slot and spaced therefrom by a distance greater than the smallest transverse dimension of said slot; and an anode having a contour substantially similar to that of said grid.

7. In an electron discharge device, a control system comprising an apertured accelerating electrode followed by a control grid having a bulged central portion extending toward the aperture of said accelerating electrode and spaced therefrom by a distance greater than at least one of the transverse dimensions of said aperture.

8. In an electron discharge device, a control system comprising a slotted accelerating electrode followed by a control grid having a bulged central portion extending toward the slot of said accelerating electrode and spaced therefrom by a distance greater than the smallest transverse dimension of said slot.

9. In an electron discharge device, a pair of control systems arranged in cascade along the path of a single electron beam, each of said systems comprising an apertured accelerating electrode followed by a control grid at a distance greater than at least one of the transverse dimensions of the aperture of the accelerating electrode, the control grid of the second control system having a bulged central portion extending

13

toward the aperture of the preceding accelerating electrode.

10. In an electron discharge device, a pair of control systems arranged in cascade along the path of a single electron beam, each control system comprising a slotted accelerating electrode followed by a control grid at a distance greater than the smallest transverse dimension of the slot of the accelerating electrode, the control grid of the second system having a bulged central portion extending toward the slot of the preceding accelerating electrode.

11. An electron discharge device comprising in the order named: an electron gun for projecting an electron beam; a first accelerating electrode included in said electron gun and having an aperture registering with said beam; a first control grid spaced from said first accelerating electrode by a distance greater than at least one of the transverse dimensions of said aperture; a second accelerating electrode having an aperture registering with said beam; a second control grid having a bulged central portion extending toward the aperture of said second accelerating electrode and spaced therefrom by a distance greater than at least one of the transverse dimensions of the aperture of said second accelerating electrode; and an anode.

12. An electron discharge device comprising in the order named: an electron gun for projecting an electron beam; a first accelerating electrode included in said electron gun and having an aperture registering with said beam; a first control grid spaced from said first accelerating electrode by a distance greater than at least one of the transverse dimensions of said aperture; a second accelerating electrode having an aperture registering with said beam; a second control grid having a bulged central portion extending toward the aperture of said second accelerating electrode and spaced therefrom by a distance greater than at least one of the transverse dimensions of the aperture of said second accelerating electrode; and an anode of contour substantially similar to that of said second grid.

13. An electron discharge device comprising in the order named: an electron gun for projecting a sheet-like electron beam of substantially rectangular cross-section; a first accelerating electrode included in said electron gun and having a slot registering with said beam; a first control grid spaced from said first accelerating electrode by a distance greater than the smallest transverse dimension of said slot; a second accelerating electrode having a slot registering with said beam; a second control grid having a bulged central portion extending toward the slot of said second accelerating electrode and spaced there-

14

from by a distance greater than the smallest transverse dimension of the slot of said second accelerating electrode; and an anode.

14. An electron discharge device comprising in the order named: an electron gun for projecting a sheet-like electron beam of substantially rectangular cross-section; a first accelerating electrode included in said electron gun and having a slot registering with said beam; a first control grid spaced from said first accelerating electrode by a distance greater than the smallest transverse dimension of said slot; a second accelerating electrode having a slot registering with said beam; a second control grid having a bulged central portion extending toward the slot of said second accelerating electrode and spaced therefrom by a distance greater than the smallest transverse dimension of the slot of said second accelerating electrode; and an anode of contour substantially similar to that of said second grid.

15. An electron discharge device comprising in the order named: an electron gun for projecting an electron beam; an accelerating electrode having an aperture registering with said beam; a control grid having a bulged central portion extending toward said aperture and spaced therefrom by a distance greater than at least one of the transverse dimensions of said aperture; and an anode having a bulged central portion substantially similar to that of said grid and having marginal portions spaced from said grid by a distance less than the spacing between said central portions.

16. An electron discharge device comprising in the order named: an electron gun for projecting a sheet-like electron beam of substantially rectangular cross-section; an accelerating electrode having a slot registering with said beam; a control grid having a bulged central portion extending toward said slot and spaced therefrom by a distance greater than the smallest transverse dimension of said slot; and an anode having a bulged central portion substantially similar to that of said grid and having marginal portions spaced from said grid by a distance less than the spacing between said central portions.
